UNITED STATES PATENT OFFICE.

HENRY JERMAIN CREIGHTON, OF SWARTHMORE, PENNSYLVANIA, ASSIGNOR TO
ATLAS POWDER COMPANY, OF WILMINGTON, DELAWARE, A CORPORATION OF
DELAWARE.

ELECTROLYSIS REDUCTION CELL.

Application filed March 26, 1926. Serial No. 97,783.

This invention relates to an electrolysis cell for carrying out certain reduction processes. It is of particular utility in reducing sugars to alcohols, and for the purposes of explanation, I will describe its construction and operation from that standpoint. However, I desire to protect the use of this cell in every relation in which it may be found of utility, because as this description proceeds, it will become apparent that any reduction which may be brought about by the use of a sodium or other alkali metal amalgam may be carried out to advantage in said cell.

In my Patent 1,612,361 of December 28, 1926, I have claimed the process of reducing sugars to alcohols by a cell like that herein shown and described.

This cell is divided into two parts by a porous diaphragm. One section of this cell (the cathodic section) contains a mercury cathode and means for agitating the same; the other section of the cell (the anodic section) contains a suitable anode material (platinum, lead dioxide, etc.). In this particular reduction process, an aqueous solution of mannose containing, for example, 5% of sodium sulphate is placed in the cathodic section. A suitable concentration for this catholyte is 15 to 25% sugar and 5% sodium sulphate. In the anodic compartment is placed an aqueous solution of sodium sulphate, for example 5%. As an example of the strength of the current and the voltage employed, I may mention that good results have been obtained with a current of one and one-half ampere per square decimeter of cathode surface, the voltage varying between 5 and 8 volts, depending upon the temperature, rate of stirring of the mercury cathode, etc. I have found the rate of stirring of the mercury cathode to be an important factor. The more violent the agitation of the mercury, the more rapidly the reduction of the sugar proceeds. It has also been found, however, that if the mercury is stirred too violently it becomes completely broken up into tiny droplets separated one from the other by a film of the catholyte, and this causes the resistance of the cell to increase enormously. I have observed that in the operation of this process, the catholyte becomes gray and opaque due to the formation of finely divided suspended mercury, the presence of which possibly aids and accelerates

the reaction. I have found it desirable to agitate the mercury as vigorously as possible 55 without undue rise in voltage. I preferably include a voltmeter X in the circuit of the cell and the operator may effectively control the rate of agitation by noting the reading of the voltmeter.

In the accompanying drawing:

Fig. 1 is a diagrammatic, vertical sectional view of the electrolysis cell of the present invention, and

Fig. 2 is a sectional view showing the stirrer or agitator hereinafter described.

Referring to the drawing, 5 designates a jar, or like container, constituting the main body of the cell. A body of mercury 6, disposed in the lower portion of the jar 5, constitutes the cathodic material of the cell and may be brought into electrical connection with the negative conductor of the cell, by means of a metallic rod or post 7, which projects downwardly through a tube 8, made of insulating material such as glass, and has its lower end disposed in the body of mercury. An agitator 9 is disposed in the body of mercury and is capable of being rotated from the exterior of the cell. As indicative of the fact that the agitator is capable of being so rotated from the exterior of the cell, I have conventionally illustrated a pulley 10 upon the shaft 11 of the agitator, but it is to be understood that any suitable means of rotating the agitator may be employed. Furthermore, various forms of agitators may be used though I have found the one illustrated to be very satisfactory. This agitator comprises the straight, oppositely inclined blades 9^a, 9^b, the lower edges of which may, advantageously, just clear the bottom of the cell and the inclination of which is such as to thoroughly stir the mercury and catholyte without excessive breaking up of the latter.

The anode 12 of the cell consists of a suitable material, such as lead or lead coated with lead dioxide. This anode is suspended in a porous cylinder 13, such as unglazed porcelain, etc., which is the porous diaphragm hereinbefore referred to. Any suitable means may be employed for suspending the porous diaphragm, the anode, the agitator and the post 7 in the body 5. As one way of accomplishing that result, I have illustrated a cap 10 or cover 14, which may be of glass, hard rub-

ber or any other suitable material, and from which the several elements mentioned are suspended. In the use of the cell in conjunction with reducing sugars, an aqueous solution of 5 mannose, or other sugar or sugars, containing an aqueous solution of sodium sulphate or other suitable electrolyte and indicated at A, is placed in the main body or cell 5, and constitutes the catholyte, hereinbefore referred 10 to, while in the porous cylinder is placed the aqueous solution of sodium sulphate or other electrolyte, hereinbefore referred to.

A specific example of the operation of the cell follows:

15 An aqueous solution containing between 15 and 25 per cent of mannose and 5 per cent of sodium sulphate is placed in the body 5 of the cell, on top of the mercury cathode 6, and the lead dioxide anode 12, contained in the 20 porous cylinder 13, is surrounded with an aqueous solution containing 5 per cent of sodium sulphate, the levels of the solutions in 5 and 13 being the same. An electric current having a strength of one and one-half amperes for every square decimeter of cathode 25 surface is passed through the cell, the mercury cathode being vigorously agitated by the agitator 9. When the current is turned on, the sulphate ions are discharged at the lead 30 dioxide anode and the discharged ions subsequently react with the water forming oxygen and sulphuric acid in the porous cylinder. In the cathodic section of the cell sodium ions 35 discharge at the mercury cathode and the resulting sodium atoms unite with the mercury, forming sodium amalgam, which subsequently decomposes the water, forming nascent hydrogen and sodium hydroxide. The nascent 40 hydrogen formed in this way reduces the mannose to mannite. Continuous decomposition of this amalgam would tend to increase continuously the alkali (sodium hydroxide) content of the catholyte as in the process previously described. This continuous increase, 45 however, is prevented by the fact that hydrogen ions migrate from the anodic section of the cell into the catholyte and there neutralize some of the alkali, and hydroxyl ions (alkali) migrate from the catholyte into the porous 50 cylinder and there neutralize some of the acid, the result of both neutralizations being the re-formation of sodium sulphate. In this way a limited amount of sodium sulphate is used over and over again. The rates of migration of these ions and other conditions are 55 such that the catholyte always remains slightly alkaline (which is an advantage since I have shown that the electrolytic reduction of sugars takes place but slowly and with 60 some sugars not at all, in an acid solution); and the anolyte always remains somewhat acid. When reduction is complete the alkaline catholyte can be rendered neutral by the addition of the acid anolyte. While, as 65 stated, the catholyte is maintained in a some-

what alkaline condition during the reduction process, the neutralization referred to may be carried to such a point that the catholyte will be almost neutral.

The diaphragm is of importance because 70 the sugar and the resulting alcohol must be prevented from coming in contact with the anode, since, otherwise, they would be oxidized. It is obvious that the diaphragm must be sufficiently porous to permit the migration 75 of the hydrogen-ions, hydroxyl-ions and sulphate-ions and at the same time sufficiently dense to prevent the diffusion of the catholyte into the anode section, but at the same time not so dense as to increase unduly the voltage 80 of the cell. The diaphragm material must also be of such a nature as to withstand the action of alkali on one side and the action of acid on the other.

The invention contemplates the use of such 85 modifications and rearrangements of parts as may be found to be desirable. For example, it would be a mere matter of choice to combine a number of the cells in a battery or to multiply the diaphragms or to vary their 90 nature, shape and arrangement. Further, I do not limit myself to the use of sodium sulphate as an electrolyte but contemplate the use of any suitable sulphate of an alkali metal, or compound of an alkali or an alkali 95 earth metal, or sulphates of two or more alkali metals, or two or more suitable compounds of alkali, or alkaline earth metals and I wish it to be understood that the term sulphate of an alkali metal is used in the appended claims in its broadest significance and is intended to include the various modifications 100 therein recited.

For example, I may use potassium sulphate, sodium carbonate, magnesium sulphate, calcium nitrate, etc.

Having described my invention, what I claim is:

1. An electrolysis cell of the character described, comprising a container, a body of 110 mercury therein constituting the cathode thereof, an agitator projecting into the mercury cathode for directly engaging and agitating the same, a porous cylinder, the interior of which constitutes the anodic section, 115 an anode in said cylinder, an anolyte in said cylinder, and a catholyte in the container and surrounding said cylinder, the walls of the cylinder being of such porosity as to prevent the passage of the catholyte into the anodic 120 section, while permitting the passage of hydrogen ions from the anodic section to the cathodic section, and the passage of hydroxyl ions from the cathodic section to the anodic section.

2. An electrolysis cell of the character described, comprising a container constituting a cathode section, a porous diaphragm separating the cathodic section from the anodic section, an anode in the anodic section, said 125

diaphragm being of such porosity as to prevent the passage of catholyte into the anodic section, while permitting the passage of hydrogen ions from the anodic section to the cathodic section, and permitting the passage of hydroxyl ions from the cathodic section to the anodic section, a body of mercury in

the cathodic section which constitutes the cathode of the cell, and means for rapidly moving and highly agitating said mercury 10 cathode, as and for the purposes set forth.

In testimony whereof he affixes his signature.

HENRY JERMAIN CREIGHTON.
